CLAIM

The ornamental design for a blood glucose sensor dispensing instrument, as shown and described.

DESCRIPTION

FIG. 1 is a perspective view of a blood glucose sensor dispensing instrument, in accordance with one embodiment; FIG. 2 is a front view of the blood glucose sensor dispensing instrument of FIG. 1, in accordance with one embodiment; FIG. 3 is a rear view of the blood glucose sensor dispensing instrument of FIG. 1, in accordance with one embodiment; FIG. 4 is a first side view of the blood glucose sensor dispensing instrument of FIG. 1, in accordance with one embodiment;

FIG. 5 is a second side view of the blood glucose sensor dispensing instrument of FIG. 1, in accordance with one embodiment;

FIG. 6 is a top view of the blood glucose sensor dispensing instrument of FIG. 1, in accordance with one embodiment; and,

FIG. 7 is a bottom view of the blood glucose sensor dispensing instrument of FIG. 1, in accordance with one embodiment.
